UNITED STATES PATENT OFFICE.

HENRY S. BLACKMORE, OF MOUNT VERNON, NEW YORK.

PROCESS OF PRODUCING HYDROGEN CARBID.

SPECIFICATION forming part of Letters Patent No. 770,214, dated September 13, 1904.

Application filed February 16, 1901. Serial No. 47,675. (No specimens.)

To all whom it may concern:

Be it known that I, HENRY SPENCER BLACKMORE, a citizen of the United States, residing at 206 South Ninth avenue, Mount Vernon, in the county of Westchester and State of New York, have invented certain new and useful Improvements in Processes of Producing Hydrogen Carbid; and I do hereby declare the following to be a full, clear, and exact description of the invention, such as will enable others skilled in the art to which it appertains to make and use the same.

The object of my invention is to produce hydrogen carbids by chemical means and in such a manner as to economize the cost of production as found hitherto; and it consists in bringing a gaseous or vaporous sulph-alkyl, commonly known as "sulfo-hydro-carbon," such as is found contaminating sulfurous petroleum, in contact with iron carbid in a heated state.

In carrying out my invention on a practical basis I proceed as follows: I take iron carbid, break the same in small pieces, place it in a retort, and heat it to a bright red. I then pass through the retort a stream of vaporous or gaseous sulph-alkyl or body containing the same, such as sulfurous petroleum, (Lima oil.) By this means the sulfur is taken up by the iron and the carbon substituted therefor, producing hydrocarbons. In this way the disagreeable sulph-alkyl in crude petroleum can be decomposed, the sulfur separating in the form of iron sulfid and the hydrocarbons produced thereby rendering the sulfurous petroleum available for enriching illuminating-gas and for many other purposes where the presence of sulfur is detrimental.

To clearly illustrate my process, I will describe the same for producing acetylene (C_2H_2) and ethylene (C_2H_4) from the sulph-alkyl methyl sulfid, (C_2H_5S), reference being had to the accompanying drawings, of which—

Figure 1 is a vertical transverse section through the dotted line xx of Fig. 2, showing retorts partially filled with metallic carbid. Fig. 2 is a vertical longitudinal section through the dotted line yy of Fig. 1; and Fig. 3 is a front view of the furnace, showing the outlet-pipes.

Similar letters indicate like parts in the various views.

A designates a retort made of any suitable material and provided with the heads B and B', the said heads being held against the flange 55 of the retort A by means of the screw-clamp C. Through the heads B passes the inlet-pipe D, provided at its inner end with a deflector e. Each retort A is provided at or near the end closed by the head B' with a suitable outlet-pipe h, controlled by valves I, said pipes communicating with a common outlet K. Retorts A are preferably heated by means of the gas-burners L, which are so arranged as to throw the flame directly under 65 the retorts, whereby the temperature may be regulated and maintained uniformly.

In employing the apparatus described in the production of acetylene (C_2H_2) and ethylene (C_2H_4) I fill the retorts A with granulated iron 70 carbid about two inches deep over the entire bottom, then close the retorts, and gradually heat the same by means of the burners L to about 360° Fahrenheit. I then introduce under ordinary atmospheric pressure the 75 sulph-alkyl methyl sulfid (C_2H_5S) into the retort A through the inlet-pipe D, which is thrown upon the surface of the heated carbid by the extended depending spreader or deflector e. As this sulph-alkyl passes over the 80 heated iron carbid the iron absorbs the sulfur therefrom, replacing the same with carbon, as shown in the following chemical formula or equation, and elevating the temperature of the ingredients to a point approaching bright 85 redness by the internal liberation of heat or heat of reaction:

The acetylene and ethylene thus produced passes through the pipes h and K to a suitable reservoir (not shown) as rapidly as possible to prevent dissociation. The heat is 95 regulated by the burners L, and the draft is controlled by the dampers z z.

It is obvious that I can use any available sulph-alkyl, either in gaseous or vaporous condition or in a pure condition or mixed with 100

hydrocarbons, as aforesaid. It is also obvious that I can employ any other metallic carbid in place of the iron carbid aforesaid, so long as the sulfur of the sulph-alkyl has greater affinity for the base of the carbid than it has for the alkyl radical with which it is combined.

The term "sulph-alkyl" employed in this specification and claims relates to sulfur-substitution products of hydrocarbons or substances containing carbon, sulfur, and hydrogen and is intended to include mercaptans as well as sulph-alkyls *per se*, the chief object of the process being to abstract the sulfur constituent therefrom and substitute for the same an equivalent of carbon, thus transforming the sulfo-hydrocarbons, which have characteristic disagreeable odor, into hydrocarbons which burn with greater luminosity. The term "metallic carbid" as employed in this specification and claims relates to a compound or union of carbon with a metal, be it normal carbid or acetylid and is not intended to include cast-iron, the carbon composition of which is questionable and never, so far as is known, reaches nine per cent. of the iron present, and which cast-iron, in view of its low-carbon content, is impracticable for the purpose of producing hydrogen carbid, as herein set forth.

One way in which I can produce iron carbid capable of being employed in my process consists in calcining anhydrous ferrocyanid of potassium in the absence of air. The reaction which takes place may be illustrated by the following chemical formula or equation:

The carbid thus produced may be separated from the cyanid by treatment with water, the carbid being insoluble. This reaction is well known and can be found in any standard work on chemistry.

I am aware that iron has been employed to remove substances having a disagreeable odor from sulfurous petroleum; but it has not as yet been determined to a certainty that the carbon content in the iron is an actual iron carbid *en masse* or that it does not consist of free carbon or normal iron carbid dissolved or occluded in metallic iron in certain small percentages. So far as is known, however, cast-iron, which is the richest, contains less than nine per cent. of actual combined carbon. I refer to this fact for the purpose of disclaiming the use of ordinary iron which may incidentally contain small and ineffective quantities of carbon for the purpose of transforming sulfo-hydrocarbons into hydrocarbons with the abstraction of sulfur and substitution of carbon in lieu thereof by the action of metallic carbid; it not being evident that the small proportion of combined carbon in proportion to the iron present in ordinary iron can be practically employed for the purpose of mak-

ing hydrogen carbid in available quantities 65 for practical use.

It is well known that sulfurous petroleums, such as Lima oil, have not been available for the purpose of producing illuminating-gas for the reason that the presence of sulfur produces deleterious effects. By employing my process in connection with the ordinary process for producing oil-gas or enriching water-gas the ordinary sulfurous petroleums may be substituted for the non-sulfurous variety, 75 with the advantage that the abstraction of sulfur by my process augments the remaining hydrocarbons of the sulfurous petroleum by supplying thereto a hydrocarbon capable of producing increased luminosity, so that instead of the sulfurous petroleums being excluded for the purposes here mentioned it now becomes available by employing my process, with the advantage of producing a gas of greater luminosity than has been obtained by 80 the employment of the usual non-sulfurous varieties of petroleum employed hitherto. All processes devised in prior art for the purification from or removal of sulfur from sulfurous petroleum or so-called "Lima oil" 90 have for their object the abstraction of the sulfur content with destruction of the contained sulfur-substitution products without supplying any available ingredient in lieu of the sulfur abstracted, while in my process the 95 hydrocarbons left after the abstraction of the sulfurous content of sulfurous petroleum are augmented or increased in value to the extent of the substitution of hydrocarbons for the sulfur content removed thereby, not only removing the sulfur with purification of the petroleum, but simultaneously producing an 100 equivalent of hydrocarbon as a substitution for the sulfur eliminated.

The term "free" as employed in this specification and claims has reference to metallic carbid free from occluding or surrounding metals or metallic ingredients which would tend to retard the action of the carbid by preventing the sulfo-hydrocarbons from coming 105 in juxtaposition with the carbid, such as would be the case of iron carbid dissolved or occluded in metallic iron as found in ordinary forms of cast-iron or in which carbid the metal exists in such a high state of proportion, atomicity, 110 or quantivalence that the carbon content falls below nine per cent. of the combined ingredient, in which cases the carbids are practically inoperative with relation to my process.

It is obvious that compositions containing metallic carbids in which the carbon content of the composition as a whole is less than nine per cent. can be employed in my process without departing from the spirit of my invention so long as the metallic carbid content *per se* 115 of the composition contains at least nine per cent. of carbon.

Having now described my invention, what

I claim as new, and desire to secure by Letters Patent, is—

- 5 1. The process of producing hydrogen carbid which consists in exposing a metallic carbid containing at least nine per cent. carbon to the action of a sulfo-hydrocarbon the sulfur content of which has greater affinity for the base of the carbid than it has for the hydrocarbon radical with which it is combined.
- 10 2. The process of producing hydrogen carbid which consists in performing a double reaction between a heated metallic carbid containing at least nine per cent. carbon and a sulfo-hydrocarbon.
- 15 3. The process of producing hydrogen carbid which consists in subjecting a metallic carbid containing at least nine per cent. carbon to the action of a gaseous compound containing a sulfo-hydrocarbon while the mixture is 20 in a heated condition.
- 25 4. The process of producing hydrogen carbid which consists in exposing a fluid compound of hydrogen, carbon, and sulfur, to the action of a metallic carbid containing at least nine per cent. carbon, the metallic base of which has greater affinity for the sulfur content of the compound employed than the sulfur content has for its combined constituents.
- 30 5. The process of producing hydrogen carbid which consists in heating iron carbid con-

taining at least nine per cent. of combined carbon, and exposing it to the action of a gaseous compound containing a sulfo-hydrocarbon the sulfur of which has greater affinity for the metallic base of the carbid than it has for the hydrocarbon radical with which it is combined. 35

6. The process of producing hydrogen carbid which consists in heating a metallic carbid containing at least nine per cent. of combined carbon and exposing it to the action of 40 sulfurous petroleum or so-called Lima oil, substantially as described.

7. The process of producing hydrogen carbid which consists in exposing a free metallic carbid containing at least nine per cent. carbon to the action of a sulfo-hydrocarbon at a 45 reacting temperature.

8. The process of producing hydrogen carbid which consists in exposing a composition containing metallic carbid, said carbid containing at least nine per cent. of carbon, to the action of a sulfo-hydrocarbon at a reacting temperature. 50

In testimony whereof I affix my signature in presence of two witnesses.

HENRY S. BLACKMORE.
